UNITED STATES PATENT OFFICE

2,525,182

EXTENSOMETER

Thomas F. Reed, Mount Lebanon, Pa., assignor
to United States Steel Corporation of Delaware,
a corporation of Delaware

Application June 28, 1946, Serial No. 679,916

3 Claims. (Cl. 235—103.5)

1

This invention relates to an extensometer and more particularly for an extensometer used to measure the percent extension in temper rolling. In temper rolling sheet steel it is desirable to cold reduce the strip sufficiently to "knock out" the yield point, but the extension for this purpose should be kept as low as possible in order to minimize work hardening. In order to exceed the minimum extension as little as possible, it is necessary to provide means for accurately measuring the extension so that it can be controlled. Many devices have been proposed for this purpose, but none have proved entirely satisfactory for various reasons.

It is an object of my invention to provide an extensometer which is simple and accurate.

This and other objects will be more apparent after referring to the following specification and attached drawing, in which the single figure is a schematic view of the extensometer of my invention as applied to a temper rolling mill.

Referring more particularly to the drawing, the reference numeral 2 indicates an uncoiler from which the strip S is uncoiled. The uncoiled strip passes over an idler or "billy" roll 4 into the work rolls 6 of a temper rolling mill which is provided with back up rolls 8 for the work rolls 6. After passing through the work rolls 6 the strip S passes over "billy" roll 10 and is coiled on the coiler 12. The peripheral speed of rolls 4 and 10 are substantially the same as the speed of the strip over these rolls so that the peripheral speed of the roll 10 will be greater than that of roll 4 by an amount directly proportional to the extension. Two identical generators 14 and 16 are connected to be driven by rolls 4 and 10, respectively. The characteristics of generators 14 and 16 are such that their voltage output increases directly in proportion to their speed so that they have a straight line speed voltage characteristic. The voltage V_2 from generator 16 is applied across the fixed side of a potentiometer and the voltage V_1 from generator 14 is applied across the variable side of the potentiometer. The potentiometer has a fixed resistance R_1 and a variable resistance R_2 . The ratio of R_1/R_2 can vary from 0 to any predetermined value. In other words, the resistance R_1 may be omitted, but it is not desirable to do so since the working range would then take up only a small percentage of the indicating scale. A self-balancing device 18 is arranged in the variable side of the potentiometer for actuating a slider 20 which determines the amount of resistance R_2 in series with the generator 14. As the amount of elongation varies the voltage output of generator 55

2

16 also varies. This causes the self-balancing device 18 to move the slider 20 in the proper direction to balance V_1 against some fraction of V_2 . The self-balancing device 18 may be of any standard make such as the "Brown Electronik" or the Leads Northrup "Micromax." An indicator (not shown) is associated with the self-balancing device 18 and will be calibrated as follows:

Let

10 Y_1 =strip speed on entering side of work rolls.
 Y_2 =strip speed on exit side of work rolls.

D_1 =diameter of roll 4.

D_2 =diameter of roll 10.

S_1 =angular speed of roll 4.

15 S_2 =angular speed of roll 10.

X =fraction of R_2 to right of slider contact.

E =per cent extension of strip in temper rolling.

K =constant

then

20 (1)
$$\frac{E}{100} = \frac{Y_2 - Y_1}{Y_1} = \frac{Y_2}{Y_1} - 1$$

(2)
$$Y_1 = \pi D_1 S_1$$

(3)
$$Y_2 = \pi D_2 S_2$$

25 (4)
$$S_1 = KV_1$$

and

(5)
$$S_2 = KV_2$$

therefore

(6)
$$Y_1 = \pi D_1 KV_1$$

30 (7)
$$Y_2 = \pi D_2 KV_2$$

Substituting the values Y_1 and Y_2 from Equations 6 and 7 in Equation 1 it will be seen that

(8)
$$\frac{E}{100} = \frac{D_2 V_2}{D_1 V_1} - 1$$

35 Let X represent the fraction of R_2 to the right of the slider contact 20, then

(9)
$$\left[\frac{R_1 + R_2(1-X)}{R_1 + R_2} \right] V_2 = V_1$$

and

(10)
$$\frac{V_2}{V_1} = \frac{R_1 + R_2}{R_1 + R_2 - R_2 X} = \frac{\frac{R_1}{R_2} + 1}{\frac{R_1}{R_2} + 1 - X}$$

45 Let

$$B = \frac{R_1}{R_2}$$

then

50 (11)
$$\frac{V_2}{V_1} = \frac{B + 1}{B + 1 - X}$$

and

(12)
$$\frac{E}{100} = \frac{D_2}{D_1} \left(\frac{B + 1}{B + 1 - X} \right) - 1$$

If the roll diameters are made equal, Equation 12 becomes:

$$(13) \quad \frac{E}{100} = \frac{B+1}{B+1-X} - 1 = \frac{X}{B+1-X}$$

For example, if the percent extension E varies from 0 to 10% as X varies from 0 to 1.00, the values of $X=1.00$ and $E=10\%$ may be substituted in Equation 13 to obtain:

$$(14) \quad \frac{10}{100} = \frac{1.00}{B+1-1.00}$$

or

$$(15) \quad B = \frac{100}{10} = 10$$

Substituting this value of B in Equation 13, the scale calibration is found to be

$$E = \frac{100X}{11-X}$$

While one embodiment of my invention has been shown and described it will be apparent that other adaptations and modifications may be made without departing from the scope of the following claims.

I claim:

1. An extensometer for determining the elongation of strip passing through a reducing machine which comprises a generator driven at a speed proportional to entering strip speed, an identical generator driven at a speed proportional to exit strip speed, a resistance in series with the second named generator, a slider in series with the first named generator and part of the said resistance for varying the amount of said resistance in series with the first named generator, and a self-balancing device in series with the slider for moving said slider to balance the voltage output of the first generator against a fraction of the voltage output of the second generator to determine the percent elongation.

2. An extensometer for determining the elongation of strip passing through a reducing ma-

chine which comprises a generator driven at a speed proportional to entering strip speed, an identical generator driven at a speed proportional to exit strip speed, a fixed resistance in series with both of the generators, a variable resistance in series with the second named generator, a slider in series with the first named generator and part of the variable resistance for varying the amount of said resistance in series with the first named generator, and a self-balancing device in series with the slider for moving said slider to balance the voltage output of the first generator against a fraction of the voltage output of the second generator to determine the percent elongation.

3. An extensometer for determining the elongation of strip passing through a reducing machine which comprises a generator driven at a speed proportional to entering strip speed, an identical generator driven at a speed proportional to exit strip speed, a potentiometer, the second named generator being connected across the fixed side of the potentiometer and the first named generator being connected across the variable side of the potentiometer, a slider, a self-balancing device in the variable side of the potentiometer for moving said slider to balance the voltage output of the first generator against a fraction of the voltage output of the second generator to determine the percent elongation.
